FURNITURE SLIP COVER

Philip Trubitz, Chicago, Ill., assignor to Sam Pass,
Chicago, Ill.

Application July 2, 1938, Serial No. 217,157

1 Claim. (Cl. 155—182)

This invention relates to improvements in furniture slip covers.

In the manufacture of ready made slip covers of the so-called one-piece construction which are intended to fit over-stuffed articles of furniture varying in size and style, considerable difficulty has been experienced heretofore in so making the covers that they smoothly fit and cover the articles of furniture at the juncture of the inner forward portions of the arms and the seat portions. Such covers are generally provided with surplus material adapted to be tucked into the spaces at the juncture of the arms and backs of the chair or davenport, as well as surplus material to be tucked into the spaces between the seat portions and the arms and lower portions of the back for holding the covers in adjusted position on the articles. The front or drop of the covers have heretofore generally been made of substantially the same transverse length as the forward transverse edge of the seat cover portion and attached throughout their length thereto and where such seat cover portions were longer than the corresponding portions of the articles on which they were placed, the covers fitted poorly at the lateral sides of the drops where they joined the respective arm cover sections.

For improving the fitting of the cover at the places mentioned, cover manufacturers frequently have left the lateral vertical edges of the drop free, that is, unattached to the arm cover sections and the purchasers were advised to either sew them in place after fitting the same to their chairs or to attach them by pinning or by snap fasteners. In many such instances, a cover fitted the chair or davenport unsatisfactorily along the front thereof where the article was of a size smaller than the maximum size on which the cover could be used since while the surplus material of the seat cover portion could be tucked into the space at the sides of the arm, no means were available for taking up the corresponding surplus material of the drop of the cover and as a result, this portion of such covers frequently lacked the smooth, snug fit that is desirable.

It is an object of the present invention to provide a slip cover so constructed that surplus material of the drop or front portion of the cover can be adjusted effectively to the length required to provide, in conjunction with the arm cover sections, a neat fit at the forward portion of the article whether such article is of a size smaller than the maximum size on which such cover might be used or is of the maximum size.

In the drawing:

Fig. 1 is a perspective view of a club chair having one of the improved covers thereon; and

Fig. 2 is an enlarged perspective view of one corner of an improved cover showing the improved drop take-up construction whereby the cover can be fitted neatly to undersized chairs at the junction of the drop with the arm cover sections.

In the drawing, a chair 10 of conventional type is shown having thereon a so-called one-piece cover, that is, the back cover section 11, the arm cover sections 12, the seat cover section 13 and the drop or front panel 14 are attached together as distinguished from covers having detachable arms, for example.

The one-piece covers of the type referred to generally are provided with surplus material at the lateral edges 13a of the seat cover section 13 whereby the same may be tucked downwardly into the space between the arm sections 10a of the chair and the seat portion 15 as well as surplus material at the rear of the cover portion 13 whereby the same may be tucked downwardly into the space at the rear of the seat portion 15. The drop 14 is shown as being connected to the seat cover portion 13 by a seam 16, this seam terminating, however, short of the ends of the drop as shown clearly in Fig. 2. This construction leaves a free portion 14a at each end of the drop 14 which is unattached to the seat cover portion 13.

With this construction, it will be obvious that in tucking the surplus material provided at the junction of an arm cover section 12 and seat cover section 13 downwardly into the space at the side of the seat 15, the end portions 14a of the drop 14 will not be drawn into such space and thereby necessarily be wrinkled, thus making an un-neat fitting drop but, on the contrary, such surplus material can be tucked downwardly into the spaces mentioned independently of the end portions 14a of the drop. The amount of material available for tucking down into such space depends, of course, upon the width of a particular chair on which the cover is to be fitted. Thus, the free portions 14a are of a width sufficient to enable the maximum amount of such surplus material to be tucked down into such spaces without drawing or wrinkling the drop 14.

As shown in Fig. 1, when the material has been tucked into such spaces, the free end portions 14a of the drop 14 are inserted beneath the front portions 12a of the arm cover sections 12, in which position they may be secured to the por-

tions 12a by any suitable means such as snap fasteners 17 or they may be actually sewed in place, if desired.

5 The forward portions of the seat cover section 13 adjacent the free ends 14a of the drop 14 preferably are provided with downwardly extending extensions or flaps 18 as shown in Fig. 2 which cover the upholstery of the article of furniture along the upper edge of the free portions 10 14a. In Fig. 2, the cover is shown extended to its maximum extent, it being understood that in fitting such cover even to a chair of the maximum width, some of the material at the juncture of the arm cover sections 12 and the seat cover section 13 will be tucked into the lateral spaces at the sides of the seat 15, thus effecting the disposition of the vertical edges of the free portions 14a beneath the front portions 12a of the respective arm covers 12.

15 20 This construction provides an unwrinkled and neat fitting cover along the vertical edges of the drop 14 whether the cover be fitted to a chair of the maximum size which it is adapted or designed to fit or an intermediate or minimum size article of furniture which would not be the case were the free end portions 14a of the drop secured to the cover section 13 by extending the seam 16 to the ends of the drop as has been general practice heretofore.

25 30 While I have shown and described an embodi-

ment of my improvements for the purpose of illustration, I do not wish to be restricted specifically thereto since variations may be made therein without departing from the spirit of the invention as defined by the appended claim.

5

What I claim as new and desire to secure by Letters Patent is:

A slip cover for articles of furniture differing in size comprising a seat cover section, arm cover sections secured thereto, a drop for covering the front of the article between said arm cover sections, said drop being attached to the seat cover section at the intermediate portion of the upper horizontal edge and unattached thereto at the end portions of such edge to provide 10 free end portions whereby the lateral portions of the seat cover section along the junction of the same with the arm cover sections can be tucked downwardly along the lateral sides of the seat of the article independently of said free 15 end portions of said drop, said free end portions extending laterally sufficiently to enable the same to be disposed in overlapping relation with the respective arm cover sections and to be attached thereto, and a flap extending downwardly from 20 the forward edge of the seat cover section adjacent each free end portion of the drop and each adapted to be overlapped by one of said free end portions.

PHILIP TRUBITZ. 30
